HARDWARE FOR MOUNTING AN OVERHEAD
GARAGE DOORFrank O. Holister, Los Angeles, and Garland
M. George, Long Beach, Calif.

Application April 2, 1945, Serial No. 586,172

7 Claims. (Cl. 16—129)

1

Our invention relates to overhead garage door hardware, and an important object of the invention is to provide non-pivotal means for adjusting the hardware to different depths of pockets at the sides of the door.

Another object of the invention is to provide such means that will effectively hold the door supporting means in its adjusted positions.

A further object is to provide an easily assembled wall bracket support that will remain lubricated over a long period of time.

Our invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a vertical sectional view, through a garage door and associated building parts, illustrating an embodiment of the foregoing objects.

Fig. 2 is an enlarged section, taken on the line 2—2 of Fig. 1, and also on the line 2—2 of Fig. 3.

Fig. 3 is a broken elevation, looking in the direction of the arrow A of Fig. 2.

Fig. 4 is an enlarged transverse section, taken on the line 4—4 of Fig. 1.

Fig. 5 is an enlarged section, taken on the line 5—5 of Fig. 1.

Fig. 6 is a broken, side elevation, looking in the direction of the arrow B of Fig. 5.

Referring more in detail to the drawings, the reference number 9 generally designates a garage door, while the side wall of the garage is suggested at 10. A board 12 spans the space between adjacent studs 13 of the garage building and in turn supports the pivotal support for the door 9.

The pivotal support comprises a dished bracket 14 that is bolted to the wall board 12, as suggested at 15. The bracket 14 has a circular opening 16 which provides a bearing for a rotating bushing 17. The bushing has an outwardly directed flange 18 that hooks inside the dished bracket 14, to hold the bushing in place.

A pair of flaring door-supporting arms 19 have straight, parallel inner ends 20. Pivoting plates

21 provide complementary channel members 22, face to face, for removably clamping the ends 20 therebetween. Bolts 23 and nuts 24 clamp the plates 21 to each other at their end portions.

5 The intermediate portions 25 of the plates 21 are permanently riveted together, as shown at 26. A circular boss 27 is pressed outwardly from the body 25 of the plate. Opposed bosses 27 on the plates 25 embrace therebetween abutting flanges 28 of bearing sleeve members 29 and 30. Rivets 31 fasten the flanges 28 in between the opposed bosses 27. The bushing 17 has a circumferential groove 32 for receiving a C-shaped, resilient ring 33. The ring 33 snaps into the groove 32 and holds the sleeve member 30 by abutting same. The other sleeve member 29 abuts the outer face of the bracket 14, and, as stated, the members 29 and 30 abut each other. A triangular-shaped pocket 34 is afforded between the adjacent corners of the flanges 28, for receiving grease, to lubricate the turning of the bearing members 29 and 30 on the bushing 17.

The outer ends 36 of the arms 19 are bent parallel with each other and are disposed at right angles to the door 9. Clamps 37 mount the ends 36 on the door. Each clamp 37 comprises a loop 38 for embracing an adjacent end 36. Integral with the loop 38 are spaced lugs 39 that are drawn together in clamping relation by bolts 40 and nuts 41. Foot tabs 42 on the lugs 39, respectively, are secured to the door 9 by suitable means, such as bolts 43.

35 Suitable counterbalancing means is provided for counterbalancing the weight of the door 9. The means shown in the drawings is a relatively strong coil spring 44 that has one end anchored to a fixed plate 45 on the garage structure, and has its other end hooked in a chain 46, which in turn is connected with a pivot bolt 47 on a clip 48.

It is believed clear, without further illustration, 40 that the construction shown in Fig. 1 may be duplicated at opposite sides of the door 9, and that counterbalancing means such as the spring 44, or any other suitable means, may be employed on one or both sides of the door.

45 In the use of our present invention, the door may be swung to the closed position (shown in full lines in Fig. 1), or to the open, overhead position (shown in broken lines in Fig. 1). A handle 49 of any desired shape or construction may be employed for manipulation of the door. The counterbalancing means 44 will assist in the lifting of the door 9 to an overhead, open position, and cushions the closing of same.

50 The space at the sides of the garage structure, inside of same, are called the "pockets" or

"offsets," which vary in size. That is, the inside width of the garage varies quite considerably, while the size of garage doors is to a considerable extent standard. Thus these pockets or offsets vary considerably.

Our present hardware compensates for these different depths. When installing, the door 9 is placed in the doorway substantially as shown in Fig. 1. The brackets 14 are bolted to suitable supports, such as shown at 12, in the pockets or offsets at the opposite sides of the building. Then the assembly of the bushing 17, bearing members 29 and 30 and pivoting plates 21, is mounted upon each bracket 14. The inner ends 20 of the arms 19 are inserted between the channel members 22, and the embracing loops 38 are placed upon the outer ends 36 of the arms. Since the ends 20 of each pair of arms 19 are held parallel in channels 22, said ends can be lightly clamped by the bolts 23. Thus lightly held, the arms 19 can be rotated in channels 22 to bring the parallel outer ends 36 into vertical alignment opposite that portion of the door to which clamps 37 are to be affixed. If the arms 19 extend too far forward, bolts 23 can be slackened off and said arms suitably retracted to bring the foot tabs 42 flat against the inner face of the door. If said arms 19 do not quite contact the door, the ends 20 can be tapped to slide the arms forwardly and thus bring said foot tabs against the door. For a shallow pocket, the mentioned rotation of arms 19 will be relatively slight in order to bring the outer ends 36 opposite the door. For deeper pockets, said rotation will be commensurately greater, as can be understood. In the latter instances, of course, the angularly directed portions of arms 19 will each lie in a plane at an angle to the plane common to the inner ends 20, the angle of said planes will be opposite and substantially equal, and the outer ends 36 will retain parallelism but reside in a common plane that is laterally offset from the plane of ends 20. With arms 19 thus arranged, bolts 23 are tightened to lock said arms against further rotation, bolts 43 are applied to secure clamps 37 to the door, and bolts 40 tightened to effect tight gripping by clamps 37 of the arm ends 36.

Clip 48 may have been previously strung on the upper arm 19 or may be applied after assembly as desired. Said clip, after adjusting the tension of spring 44, may be then locked in place on said arm by tightening bolt 47. It is understood that the hardware at both sides of the door are applied in the above manner regardless of variations in the sizes or depths of the pockets or offsets. Only the degree of rotation of the arms 19 varies as above indicated.

Having thus described our invention, what we claim and desire to secure by Letters Patent is:

1. Hardware for mounting an overhead door in a structure having opposed side walls spaced further apart than the width of said door to provide pockets laterally of the door, said hardware comprising a support embodying a pivot shaft extending inward from a side wall of the structure in one of the pockets, a pair of plate members pivotally mounted on the shaft and formed with oppositely disposed and parallel channels, arms having parallel inner ends in the channels of the plate members and adapted for both rotational and endwise adjustment therein, the arms having intermediate portions that are angularly directed away from each other and having outer ends that are parallel to each other and to the inner ends engaged in said channels, clamp means on said plate members for constricting said chan-

nels to clamp said inner ends of the arms against rotational and endwise movement and means for connecting the outer ends of the arms substantially at right angles to the door.

2. Hardware for mounting an overhead door in a structure having opposed side walls spaced further apart than the width of said door to provide pockets laterally of the door, said hardware comprising a support embodying a pivot shaft extending inward from a side wall of the structure in one of the pockets, a pair of plate members pivotally mounted on the shaft and formed with oppositely disposed and parallel channels, arms having parallel inner ends in the channels of the plate members and adapted for both rotational and endwise adjustment therein, the arms having intermediate portions that are angularly directed away from each other and having outer ends that are parallel to each other and to the inner ends engaged in said channels, clamp means on said plate members for constricting said channels to clamp said inner ends of the arms against rotational and endwise movement and a clamp bracket on the outer end of each arm arranged for securing the outer ends of the arms substantially at right angles to the door.

3. In a structure having opposed side walls and an overhead closure door, hardware for mounting said door on said structure and comprising a frame pivotally mounted on a side wall and connected to the door, the frame comprising a pair of arms having intermediate angularly diverging portions, the arms having inner parallel ends, a pair of plate members having channels for receiving said inner ends for rotational and endwise adjustment and including clamping means therefor to hold the same adjusted, the arms having outer parallel ends, and means connecting said outer ends to said door.

4. In a structure having opposed side walls and an overhead closure door, hardware for mounting said door on said structure and including a group of elements operatively connecting a side wall and the door, the group of elements comprising a pair of arms having diverging intermediate portions terminating at one end in closely adjacent parallel tubular portions and at the other in parallel portions that are spaced further apart, said tubular portions being disposed in a plane parallel to the planes of said side walls, means connected to a wall of said structure for rotation in a plane parallel to the plane of said wall and for receiving the adjacent tubular portions of said pair of arms to mount the same for adjustable rotational movement on the axes of the respective tubular portions whereby the further spaced portions of the arms are adapted to be adjusted to reside in a plane parallel to and offset from the plane of the adjacent arm portions, and means for connecting said further spaced portions to the door.

5. Hardware for mounting an overhead door in a structure having a pocket at least at one side of the door, said hardware comprising adjustable pivot means adapted to be mounted in said pocket and rotatable about a horizontal axis, arms having substantially parallel inner tubular ends, clamping means on the pivot means arranged to clamp said tubular ends against rotational movement, said tubular ends, upon loosening of the clamping means, being rotatively adjustable around their respective axes, the arms having intermediate portions that diverge and having outer ends that are substantially parallel to each other and to the inner ends, and clamp-

ing means on the outer end of each arm arranged to secure the outer ends of the arms substantially at right angles to the door.

6. A hanger for an overhead opening garage door comprising a bracket support adapted to be secured to the inside wall of a garage, said bracket support including a pivot bearing member, a pair of cooperating clamped plate members mounted on said pivot bearing member and having oppositely disposed, longitudinal complementary grooves, longitudinally adjustable arms having a pair of ends in said grooves, each arm having parallel offset end portions and an intermediate connecting portion, said arms being round in cross-section and said grooves defining sockets wherein said arms are mounted for rotative adjustment about the longitudinal axes of the sockets and secured by said clamped plate members, and means for adjustably securing the outer ends of said arms to a garage door.

7. A hanger for an overhead opening garage door in a structure having opposed side walls comprising a support embodying a pivot shaft extending inward from a side wall of the structure, clamping means mounted on said pivot shaft, a pair of arms, each arm having parallel offset cylindrical end portions and an intermediate connecting portion, the inner ends of the arms being embraced
